(57) **CLAIM**

I claim the ornamental design for a magnetic hook, as shown and described.

DESCRIPTION

FIG. 1 is a front perspective hook of a magnetic hook;

FIG. 2 is a first side view of said magnetic hook;

FIG. 3 is a second side view of said magnetic hook;

FIG. 4 is a front view of said magnetic hook;

FIG. 5 is a rear view of said magnetic hook;

FIG. 6 is a top view of said magnetic hook; and,

FIG. 7 is a bottom view of said magnetic hook.

The broken lines represent environment and forms no part of the claim.
